WINDOW WELL COVER

Richard H. Frost, Bow Mar, Colo., assignor to Frost Engineering Development Corporation, Denver, Colo., a corporation of Colorado

Filed Dec. 21, 1961, Ser. No. 68,020

Term of patent 14 years

(Cl. D13—1)

FIG. 1.

FIG. 2.

FIG. 3.

FIG. 4.

The bottom plan view of the right half and the side elevation as seen looking to the right in FIGURE 1 are mirror images of FIGURES 4 and 5, respectively.

I claim:

The ornamental design for a window well cover, as shown and described.
